LOCOMOTIVE TENDER

Nathan M. Lower, Erie, Pa., and Charles J. Surdy,
New York, N. Y., assignors to The Standard
Stoker Company, Incorporated, a corporation
of Delaware

Application December 16, 1937, Serial No. 180,094

7 Claims. (Cl. 105—234)

This invention relates to locomotive tenders of the type equipped with stoker conveying mechanism.

It is the principal object of this invention to provide a drive means for the stoker conveyor mechanism, which drive means is so related with the tender and the stoker conveyor mechanism that inspection, repair and lubrication of said drive means may be readily accomplished.

10 A further object of this invention is to provide improved means for lubricating drive means of locomotive stoker mechanism, which stoker mechanism includes a trough or casing member immersed in the water.

15 A still further object of this invention is to provide means for draining the lubricant from the stoker conveyor drive means, such drainage means passing freely through an aperture in the stoker trough or casing.

20 Other objects will become apparent upon reading the following description of our invention in connection with the accompanying drawing, in which

Fig. 1 is a medial vertical section taken longitudinally through the forward portion of a locomotive tender with the invention in similar section;

Fig. 2 is an enlarged view of the rear part of Fig. 1;

30 Fig. 3 is a view similar to a portion of Fig. 2 illustrating a modification, and

Fig. 4 is a sectional view taken on the line 4—4 of Fig. 2.

Referring first to Figs. 1, 2, and 4, the tender 35 T is provided with a tank or cistern 10 which is mounted upon an underframe 11. Cistern 10 includes a water compartment 12 and a fuel bin 13 which is defined by a bottom plate 14, the rear slope plate 15 and side plates such as 16. The 40 plates 14, 15 and 16 separate the fuel and water compartments 13 and 12, respectively.

The conveying mechanism of the locomotive stoker is indicated generally at C and includes a trough conduit or casing 17 which is in open 45 communication with the fuel bin 13 through an aperture 18 in the bottom plate 14. Preferably, the stoker trough 17 is secured to the bottom plate 14 in water-tight fashion so that the trough may be immersed in the water. Shiftable plates 50 19 are mounted across the aperture 18 and are adapted to regulate its effective size.

The trough conduit 17, which is approximately V-shaped in transverse cross section, is provided with foot members 20 for supporting it from the 55 underframe 11. A conveyor screw 21, rotatably

mounted in the trough conduit 17, urges fuel forwardly against a crusher 22 whereby large lumps are reduced to a size more suitable for economical firing. The crusher 22 is secured to the inner side of front wall 23 of the trough conduit 17. To the other side of the front wall 23 is secured a spherical shell 24, forming one element of a ball and socket joint between the trough conduit 17 and a conduit leading forwardly toward the locomotive (not shown). The rearward portion of the trough conduit 17 is provided with a well 25, the bottom 27 of which is spaced above the tender frame 11.

The operating mechanism for driving the conveyor screw 21 includes a gear reduction unit 28 housed with a gear case 29. The gear case 29 is disposed within the well 25 and is provided with a flange 30 in abutting relations with a flange or rim 31 formed interiorly of the well 25. Studs 32 are screwed into the flange 31 for receiving the flange 30 of the gear case 29. A cover 33 closes the open forward side of the gear case 29 and is provided with suitable holes for engagement by studs 32. A nut 34 is threaded over the outward end of each stud 32 whereby the cover 33 is secured to the gear case 29 and the cover 33 and gear case 29 are securely attached to the flange 31 of the well 25. Bolts 35 are also passed through the flange 30 of the gear case 29 and cover 33 so that the latter may be secured to the former independently of the means which secures the gear case 29 to the trough conduit well 25.

In approximate axial alignment with the conveyor screw 21 is a shaft 36, journaled in the gear case 29 and cover 33, said shaft 36 being provided with a polygonal outward portion 37 in driving engagement with the rearward end of the conveyor screw 21. Interiorly of the gear case 29, the shaft 36 has secured thereon a gear 38 which is driven by a suitable pinion gear (not shown). The well structure 25 extends forward of the gear case 29, forming an upward opening 40 which is directed into the V-shaped portion of the trough conduit 17. In order to prevent coal from passing into the well structure 25, a removable plate 39 is placed over the opening 40.

The gears and shafts within the case 29 are lubricated by a lubricant which is in somewhat fluid state. A plug 41 is threaded into an opening in the top wall 42 of the gear case 29. Removal of the plug 41 is accomplished from a position in the fuel bin 13 by removing the cap 43 which is secured to the top wall 44 of the well structure 25. Threaded into the bottom wall 45 of the gear case 29 is a pipe 46 which communi- 55

cates with the interior of the gear case and extends downwardly to a point below the tender underframe 11. The pipe 46 is provided at its lower end with a removable plug 47. An aperture 48 is formed in the bottom wall 27 of the well structure 25 so that the pipe 46 may pass freely therethrough and through a sleeve 49 mounted between said bottom wall 27 and the underframe 11.

10 Since the bottom wall 27 is lower than the remainder of the trough conduit 17, water which is often present in the fuel bin 13 will drain into the well structure 25 and pass downwardly through the sleeve 49. The flange or rim 31 is 15 cut away at 50 in order that free drainage of water may be attained.

In Fig. 3, the gear case 60 is constructed as an integral part of the trough conduit 61 in order that the extent of the well structure 62 20 may be reduced. The cover 63, in this instance, carries a lubricant drain pipe 64 which passes downwardly through the sleeve 65. This lubricant drain pipe 64 is provided with a removable plug 66 at its lower end. As in the preferred 25 form, a lubricant filler plug 67 is provided in the top wall 68 of the gear case 60. A cap 69 may be utilized to cover the plug 67. This cap 69 is secured to the bottom plate 14 of the fuel bin 13. In all other respects, this form of the 30 invention is similar to the preferred form. The lubricant in the gear case may be drained by removing a plug located below the underframe 11, and this will be recognized by those familiar with the art as a distinct improvement over past practise. The plug in the top wall of the 35 gear case is utilized for replenishing the supply of lubricant and also for introducing a cleansing fluid into such gear case.

The gear case 29 is removable through the 40 aperture 18 when the shiftable plates 19 are in the position shown in Fig. 1. It is necessary first to move plate 39 forwardly and then uncouple the conveyor screw 21, whereupon the gear case 29 and cover 33 may be removed by 45 loosening nuts 34. The pipe 46 may also be withdrawn through the sleeve 49 by proper angling of the gear case 29. In the modification illustrated in Fig. 3, only the cover 63 is arranged for removal and it will be apparent that the lubricant drain pipe 64 may also be withdrawn together with the cover 63.

From the foregoing, it will be apparent that a novel method of lubrication for the stoker conveyor drive mechanism has been provided. 55 The arrangement is especially adaptable for stoker conveyors which are disposed within the water compartment of a locomotive tender.

We claim:

1. In a locomotive tender having an under- 60 frame, a tank above said underframe including a fuel compartment and a water compartment, and partition plates separating said fuel and water compartments including a plate forming the bottom of said fuel compartment, a stoker conveyor including a conduit disposed within the water compartment and having an open mouth arranged to receive fuel from said fuel compartment, a fuel conveyor mounted in said conduit for urging fuel forwardly, drive mechanism at 65 the rear of said fuel conveyor operatively connected thereto, said drive mechanism including a gear case and gearing therein, means providing access to said gear case from said fuel compartment for introducing a lubricant into said 70 gear case, and a lubricant drain extending from 75

the bottom of said gear case, through said water compartment, and below said underframe, said gear case and drain being removable from its operative position through the open mouth of said conduit into said fuel compartment. 5

2. In a locomotive tender having an underframe, a tank above said underframe including a fuel compartment and a water compartment, and partition plates separating said fuel and water compartments including a plate forming the bottom of said fuel compartment, a stoker conveyor including a conduit disposed within the water compartment and having an open mouth arranged to receive fuel from said fuel compartment, a fuel conveyor mounted in said conduit for urging fuel forwardly, drive mechanism at the rear of said fuel conveyor operatively connected thereto, said drive mechanism including a gear case and gearing therein, said gear case and the bottom of said fuel compartment having openings therein providing access to said gear case from said fuel compartment for introducing a lubricant into said gear case, a lubricant drain extending from the bottom of said gear case, through said water compartment, and below said underframe, and means for shielding said lubricant drain from the water in said last named compartment, said gear case and drain being removable from its operative position through the open mouth of said conduit into said fuel compartment. 20

3. In a locomotive tender having an underframe, a tank above said underframe including a fuel compartment and a water compartment, and partition plates separating said fuel and water compartments including a plate forming the bottom of said fuel compartment, a stoker conveyor including a conduit disposed within the water compartment and arranged to receive fuel from said fuel compartment, a fuel conveyor 40 mounted in said conduit for urging fuel forwardly, drive mechanism at the rear of said fuel conveyor operatively connected thereto, said drive mechanism including a gear case and gearing therein, said gear case and one of said partition plates each having an opening providing access from said fuel compartment for introducing a lubricant into said gear case, a lubricant drain extending from the bottom of said gear case, through said water compartment, and below said underframe, and means for shielding said lubricant drain from the water in said last named compartment, said last named means forming a passage between said conduit and said underframe. 50

4. In a locomotive tender having an underframe, a tank above said underframe including a fuel compartment and a water compartment, and partition plates separating said fuel and water compartments including a plate forming the bottom of said fuel compartment, a stoker conveyor including a conduit disposed within the water compartment having an open mouth communicating with said fuel compartment to receive fuel therefrom, a fuel conveyor mounted in said conduit for urging fuel forwardly, drive mechanism in said conduit at the rear of said fuel conveyor operatively connected thereto, said drive mechanism including a gear case and gearing therein, means accessible from said fuel compartment for introducing a lubricant into said gear case, a lubricant drain extending from the bottom of said gear case, through said water compartment, and below said underframe, and means for shielding said lubricant drain from the 65

water in said last named compartment, said gear case and drain being removable from its operative position through the open mouth of said conduit into said fuel compartment.

5. In a locomotive tender having an under-frame, a tank above said underframe including a fuel compartment and a water compartment, and partition plates separating said fuel and water compartments including a plate forming the bottom of said fuel compartment, a stoker conveyor including a conduit disposed within the water compartment having an open mouth communicating with said fuel compartment to receive fuel therefrom, a fuel conveyor mounted in said conduit for urging fuel forwardly, drive mechanism in said conduit at the rear of said fuel conveyor operatively connected thereto, said drive mechanism including a gear case and gearing therein, means accessible from said fuel compartment for introducing a lubricant into said gear case, a lubricant drain extending from the bottom of said gear case, through said water compartment, and below said underframe, and means for shielding said lubricant drain from the water in said last named compartment, said last named means forming a passage between said conduit and said underframe, said gear case and drain being removable from its operative position through the open mouth of said conduit into said fuel compartment.

6. In a locomotive tender having an under-frame, a tank above said underframe including a fuel compartment and a water compartment, a stoker conveyor including a conduit arranged to receive fuel from said fuel compartment, a fuel conveyor mounted in said conduit for urging fuel forwardly, drive mechanism immediately at the rear of said fuel conveyor operatively

connected thereto, said drive mechanism including a gear case and gearing therein, means providing access to said gear case from said fuel compartment for introducing a lubricant into said gear case, a lubricant drain extending from the bottom of said gear case through said water compartment to a point below said underframe, and means for shielding said lubricant drain from the water in said water compartment, said last named means forming a passage between said conduit and said underframe. 10

7. In a locomotive tender having an under-frame, a tank above said underframe including a fuel compartment and a water compartment, and partition plates separating said fuel and water compartments including a plate forming the bottom of said fuel compartment, a stoker conveyor including a conduit disposed within the water compartment having an open mouth communicating with said fuel compartment to receive fuel therefrom, a fuel conveyor mounted in said conduit for urging fuel forwardly, drive mechanism in said conduit at the rear of said fuel conveyor operatively connected thereto, said drive mechanism including gearing and a cover for said gearing, means accessible from said fuel compartment for introducing a lubricant to the gearing, a lubricant drain extending from the bottom of said gearing, through said water compartment, and below said underframe, and means 25 for shielding said lubricant drain from the water in said last-named compartment, said gearing, gear cover and drain being removable from its operative position through the open mouth of said conduit into said fuel compartment. 30
